US00D950512S

(12) **United States Design Patent** (10) Patent No.: **US D950,512 S**
(45) Date of Patent: ** *May 3, 2022

(54) **MOBILE PHONE**

(71) Applicant: **BEIJING XIAOMI MOBILE SOFTWARE CO., LTD.**, Beijing (CN)

(72) Inventors: **Yin Zhu**, Beijing (CN); **Fei Gao**, Beijing (CN); **Chengyuan He**, Beijing (CN); **Jianting Li**, Beijing (CN); **Jiasheng Huang**, Beijing (CN); **Yangyang Cai**, Beijing (CN); **Yafei Gu**, Beijing (CN); **Yake Hao**, Beijing (CN); **Shengyu Gong**, Beijing (CN); **Geshi Zhu**, Beijing (CN); **Tong Chen**, Beijing (CN)

(73) Assignee: **BEIJING XIAOMI MOBILE SOFTWARE CO., LTD.**, Beijing (CN)

(*) Notice: This patent is subject to a terminal disclaimer.

(**) Term: **15 Years**

(21) Appl. No.: **35/508,754**

(22) Filed: **May 7, 2019**

(80) **Hague Agreement Data**

Int. Filing Date: **May 7, 2019**

Int. Reg. No.: **DM/206188**

Int. Reg. Date: **May 7, 2019**

Int. Reg. Pub. Date: **Mar. 6, 2020**

(30) **Foreign Application Priority Data**

Nov. 7, 2018 (CN) 201830628658.6

(51) **LOC (13) Cl.** **14-03**

(52) **U.S. Cl.**

USPC ..... **D14/138 G**

(58) **Field of Classification Search**

USPC ..... D14/138, 138 C, 138 AA, 138 G, 203.1, D14/203.3, 203.5, 203.7, 248, 341, 345, D14/496; D21/329, 517
CPC . G06F 1/1626; H04M 1/0266; H04M 1/0202; H04M 1/026

See application file for complete search history.

(57) **CLAIM**

The ornamental design for a mobile phone, as shown and described.

DESCRIPTION

1. Mobile phone
- 1.1 : Front
- 1.2 : Back
- 1.3 : Left
- 1.4 : Top
- 1.5 : Bottom
- 1.6 : Front perspective view
- 1.7 : Back perspective view

1 Claim, 7 Drawing Sheets
